UNITED STATES PATENT OFFICE

2,473,667

SPRAY GUN

Michael M. Warner, Chicago, Ill.

Application June 14, 1945, Serial No. 599,434

2 Claims. (Cl. 299—88)

1

My invention relates to spray guns adapted particularly for spraying liquids such as paints, enamels, or chemicals.

Heretofore, in the use of spray guns, the cans or containers for the liquid to be sprayed were separate from the gun and connected thereto by hose or other conducting means, and with such liquid conducting hose and an air hose extending from the gun, easy and accurate operation of the gun might be interfered with.

An important object of my invention is to produce a spray gun having a bore or chamber into which liquid containers can readily be inserted for connection with the sprayer nozzle.

A further object is to provide a bore through the grip portion of the gun into which cylindrical bottles or cans containing the liquid may be readily inserted for connection with the sprayer nozzle.

A further object is to provide an arrangement in which a discharge pipe projects from the gun barrel axially through the bore in the grip for extending into the bottle or can when inserted into the bore for conducting the bottle or can contents to the barrel for discharge through the nozzle.

The above referred to and other features of my invention are embodied in the structure shown on the drawings, in which:

Figure 1 is a side elevation of the gun;

Figure 2 is a plan view;

Figure 3 is an enlarged section on plane III—III Figure 2; and

Figure 4 is a section on plane IV—IV Figure 3.

The main frame of the spray gun shown is preferably formed of halves 10 which may be molded integral preferably of plastic material and which are detachably secured together as by screws 11 to form a body portion 12 and a handle or grip portion 13 depending therefrom. When the halves 10 are secured together, the body portion 12 provides the cylindrical bore 14 for receiving a barrel 15. Extending into the outer portion of the barrel is the bore 16 threaded at its outer end for receiving a spray nozzle 17.

Extending rearwardly from the body part 12 and clamped between the halves 10 is a housing 18 having the upper bore 19 therethrough and the lower bore 20. A plug 21 has threaded engagement in the outer end of the bore 19 and has the valve stem 22 extending therefrom through the passageway 23 in the barrel 15 and the bore 16, the stem terminating in the needle valve end 24 co-operating with the outlet end of the nozzle 17 to control the volume of flow from

2

the nozzle. An air cap 25 is threaded on the outer end of the barrel 15 to surround the nozzle and the interior of the cap is connected with the bore 19 through the passageway 26 in the barrel.

Threading into the outer end of the bore 20 is a plug 27 having the passageway 28 therethrough for air flow and having the threaded nipple end 29 for receiving a coupling (not shown) for connecting an air hose with the plug. 5 The bore 29 is connected by a passage 30 with the bore 19 for flow of air through the passageway 26 and air cap past the end of the nozzle. In advance of the passage 30, a valve seat member 31 in the bore 20 provides the chamber 32 10 within which is the ball valve 33 for controlling the passageway 34 through the valve seat member, a spring 35 within the valve chamber tending to hold the valve in closed position.

In the front end of the bore 20 a plunger 36 15 is slidable, the stem or pin extension 37 at its outer end projecting into the passageway 34 through the seat member 31. Extending through the body part 12 below the barrel 15 is a rectangular guide passage 38 for the trigger slide 39 20 which at its forward end has a trigger member 40 secured thereto. In its rear end the trigger slide has a T slot 41 for receiving the T head at the inner end of the plunger 36. When the gun is at rest, the ball valve 33 is held closed by the 25 spring 35, the spring pressure being exerted through the ball against the stem end 37 of the plunger to hold this plunger and the trigger slide in outer position. Now, when the gun is to be used, the finger of the hand grasping the handle part 13 will engage with the trigger to shift the trigger slide and the plunger 36 rearwardly for unseating of the ball valve 33 by the plunger stem end 37 so that air under pressure may then flow through the air cap at the nozzle.

Extending through the grip or handle portion 13 is the bore 43 forming a chamber for receiving containers 44 of the liquid to be sprayed. Extending through the bore is a delivery tube 45 which is secured at its upper end in the barrel 45 15 for communicating with the barrel bore 16, the trigger slide having the clearance passageway 46 therethrough for the tube so that the tube will not interfere with the operation of the trigger slide for control of the air valve.

50 Welded to the tube 45 is a washer 47 which, when the tube is in service position, is located at the upper end of the bore 43. Below the washer a compression spring 48 encircles the tube for engaging against the washer 49 slidable on the tube and faced by a sealing washer 50. The

container 44 shown is cylindrical and may be of transparent material such as glass. The containers have threaded necks for closure thereof by closure caps (not shown) when the containers are not in service. When the contents of a container are to be sprayed, its cap is removed and the container slipped up into the bore 43 to receive the discharge tube 45, the edge of the container then coming into engagement with the sealing washer 50 for upward movement of the sealing washer and the washer 49 against resistance of the spring 48 so that the mouth of the container will be substantially closed. To hold the container in service position a slide cover 51 is provided for the lower end of the bore 43, this slide cover having flanges 52 engaging in guideways 53 in the end of the handle or grip part 13. After insertion of the container and closure of the cover 51, the lower end of the tube 45 will be close to the bottom of the container, and when the trigger is now set for opening of the valve 33, air under pressure will flow through the air cap 25 past the outer end of the nozzle for creating suction in the nozzle and in the bore 16 and tube 45 which will draw the can contents out through the nozzle and into the air stream for comminution and atomizing or spraying thereof. When a container is emptied, the slide cover 51 is opened and the empty container withdrawn, the spring 48 then shifting the washers 49 and 50 down into engagement with an abutment on the tube 45, which abutment may be in the form of a snap ring 54 on the tube. When another container is now inserted into the bore 43, the washers will be moved away from the snap ring to be held in closing engagement with the container mouth by the force of the spring 48. At the end of the grip part 13 openings 55 may be provided which may function as sight openings when the containers are of transparent material for determining when the containers have been emptied, or for determining the nature or color of the fluid in the containers. These passageways 55 also connect the bore 43 with the atmosphere, there being sufficient clearance between the washers 49 and 50 and the tube 45 for entrance of air into the container to compensate for the volume of liquid withdrawn therefrom during a spraying operation.

My improved spray gun is of particular utility and advantage where comparatively small quantities of different colored paints or enamels, or different chemicals, are to be sprayed, the change from one color to another or from one chemical to another being quickly accomplished by the insertion of the containers into the handle bore. Furthermore, the insertion of the containers into the gun for direct connection with the nozzle through the discharge tube in the gun, eliminates the use of hose heretofore necessary for connecting containers separate from the gun with the gun nozzle, and the gun may thus be more readily and accurately manipulated and operated.

I have shown a practical and efficient embodiment of the features of my invention, but I do not desire to be limited to the exact construction, arrangement and operation shown and described, as changes and modifications may be made without departing from the scope of the invention as defined in the appended claims.

I claim as my invention:

1. A spray gun comprising a body portion and a grip portion, said body portion including an air passageway and a paint passageway disposed longitudinally therein, a conical nozzle connected to said passageways with the paint passageway centrally disposed and the air passageway forming an annular discharge orifice about said paint passageway, a spring-pressed valve controlling flow of air into said air passageway, a sliding rod mounted in the body for transmitting the movement of the operator's finger directly by a sliding movement to said valve for unseating the same to permit flow of air into said air passageway, said grip member abutting said body portion and having a chamber therein and a paint container disposed in said chamber in communication with the paint passageway of said body portion.
2. A spray gun comprising two oppositely disposed half portions, each including an integrally formed handle and body half portion, the body portion of each half having a semi-cylindrical recess portion for forming a cylindrical bore and the handle portion of each half having a recessed portion for forming a chamber when the halves are assembled, a barrel positioned in said cylindrical bore having separate air and paint passageways longitudinally therein, a valve supported by said barrel controlling the flow of air to said air passageway, a rod disposed for longitudinal sliding movement between the assembled body portions for transmitting the movement of the operator's finger to said valve for unseating the same to admit air to said passageway and a paint container mounted in the chamber of said handle portion and in communication with the paint passageway of said barrel.
